INNER SPRING UNIT

William E. Wunderlich, Muncie, Ind.

Application October 18, 1941, Serial No. 415,525

1 Claim. (Cl. 5—269)

This invention relates to a spring unit including a plurality of open or untied coil springs the several springs being positioned in parallel rows, the immediately adjacent successive springs in successive adjacent initial rows having an alignment transverse to that of the initial rows, the several said transverse alignments being parallel to each other. Herein the springs in each initial row do not overlap or contact but are spaced apart in the row.

One chief object of this invention is to produce a spring unit wherein one face of the unit, for example, the bottom, is preferably stabilized in one direction and the top or other face of the unit is stabilized in the transverse direction.

Another chief object of the invention is to produce an end spring with an end turn which is of rigidizing and reenforcing character at its free or united end and which, approximately opposite therefrom, is provided with an offset anchoring portion.

One feature of the invention consists in providing the aforesaid free end of the coil spring with an inwardly directed tip which is of helical locking character, as hereinafter set forth.

Another feature of the invention is in providing in an end turn of a spring coil an elongated portion at the free end thereof and a similar portion in alignment therewith and at the start of said end turn, the alignment being parallel to a similarly elongated portion in the said end turn intermediate the aligned portions thereof, said similarly elongated portion being offset relative to the immediately adjacent portions of said end turn.

Two forms of coil springs are disclosed and two forms of units, each unit embodying one of the forms of coil springs. In certain spring units the coils may be of other than double helical type as herein illustrated.

Other objects and features of the invention will be set forth more fully hereinafter.

The full nature of the invention will be understood from the accompanying drawings and the following description and claims:

Fig. 1 is a partial top plan view of one embodiment of the invention, adjacent coils in adjacent rows having offset portions in lapping relation, the free end of one of said coils being aligned therewith.

Fig. 2 is a similar view of a modified form of the invention, wherein the opposite offset portion of one coil is interposed between the free end and offset portion immediately adjacent said free end in the other coil.

Fig. 3 is a perspective view of a unit with one form of double conical coil showing the end turns thereof similarly formed but positioned in transverse relation for the purpose hereinafter set forth.

Fig. 4 is a partial plan view of the top portion of a spring structure embodying spring units of Fig. 3.

Fig. 5 is a corresponding view of the bottom portion of the same structure, intermediate portions being broken out in both Figs. 4 and 5.

In Fig. 1 of the drawings, it will be noted there is illustrated a plurality of coil springs 10, all being substantially identical and having the end turn 11 provided with a free end 12 that is comparatively straight and of an appreciable length. This free end 12 is preferably provided with an inwardly directed tip 13.

Extending transversely of the free end 12 is 20 a relatively elongated portion 14 that terminates in a curved portion 15, in turn terminating in a U-shaped, outwardly directed offset portion 16, the same being positioned approximately opposite or half-way from the end of the last turn of 25 the coil. Extending from the opposite end of the offset portion 16 is the portion 17 and this completes the end turn, the same, however, terminating in a similarly but oppositely offset portion 18, the same having a midportion comparatively straight and substantially parallel to the midportion of the offset portion 16 and in substantial alignment with the straight free end 12.

The basic coil spring, in its preferred form, is 30 of double cone type with similar end turns, the end turns, however, being displaced approximately 90° of each about the spring's longitudinal axis.

As shown in Fig. 1, the portion 18 and the portion 16 of two adjacent coils in two adjacent rows are lapped and encircled by a helix 19 of comparatively small diameter. This helix 19 also encircles the comparatively straight free end 12 and this free end serves to stabilize said spring tying helix.

It will be observed that in Fig. 1 all of the helices are parallel insofar as all of the intermediate or interior spring coils are concerned.

It also will be noted the tip 13 extends through the helix 19 toward the coil axis and serves to lock the helix against longitudinal displacement with respect to the aforementioned alignment.

There is provided any suitable border wire means, preferably in the form of a helix 20, and the ends of the helices 19 are suitably associated

with th helix 20 and turned back and inwardly as at 21.

It will be understood that the extreme right hand end coils, not shown in Fig. 1, have their portions 16 associated with the border wire 20 in the usual manner and that the left hand end coils, shown in Fig. 1 have their portions 18 and 12 associated with the border wire 20 in substantially the same manner as the same portions of intermediate rows of coils have their portions associated with the helices 19.

The aforesaid construction by reason of the portions 12 and 14, provides for greater rigidity in the top plane of the spring unit than has heretofore been effected and the respective helices are locked by the tips 13 of the coils associated therewith.

In Fig. 2 a somewhat similar form of the invention is illustrated and this form is characterized by the following distinctions: parts being designated by numerals of the 100 series, to-wit, the portion 112 with the tip 113 is substantially the same as that previously described. The straight portion 114 is not as long as the portion 14 but is of considerable length. The rectangular relationship between the portions 12 and 14, and 112 and 114 is substantially the same. The portion 115, however, is arched outwardly beyond the portion 114 as illustrated. In other words, the portion 114 is not tangential to portion 115 as is the case with the portion 14 with respect to the curved portion 15.

In this form of the invention also the outwardly offset portion 116 is not substantially opposite the free end 112 of the coil but is slightly offset so that it is not immediately or diametrically opposite the latter or the portion 118. Portion 118 is of offset character relative to the immediately contiguous portions of the end turn and in alignment with the portion 112. Portion 116 is intermediate the same but on the opposite side of the end turn. The purpose of this displacement, as it were, of the portions 116 and 118 is to insure a sequential nesting arrangement as illustrated in Fig. 2 when the several coils in the several rows are associated together and connected by the helices 119 by sequential nesting arrangement, reference is had to the central portion of Fig. 2 and therein it is observed that the interfitting of one coil portion 116 between portions 112 and 118 of the adjacent coil includes in sequence the portion 118 of one end turn of one spring coil aligned with portion 116 of a similar end turn of an adjacent spring coil in turn aligned with the free end portion 112 of the first mentioned coil spring end turn and all united by helix 119. Portions 18 and 16 lap or may be positioned side by side in Fig. 1. This is one difference between the units inherent to the difference in end turn formation of the coils.

In view of the previous description, no further comment is believed necessary for an understanding of this construction.

It is to be observed that with the nested form shown in Fig. 2, the connecting helices 119 are stabilized along the longitudinal axis thereof by the several associated coil portions to a slightly greater extent than that shown in Fig. 1. However, the tying arrangement, as it were, between the coils of adjacent rows is of looser character in Fig. 2 than that obtained in the embodiment illustrated in Fig. 1.

Reference now will be had to Fig. 3. Herein there is illustrated a single coil of the type shown

in Fig. 2. This coil has its parts similarly designated by numerals of the two hundred series. It is to be observed that the coil in this case is of double conical type and at opposite ends of the coil, to-wit, the end turns of the same are similarly formed. However, as illustrated in Fig. 3, the similar formations in one end turn are displaced, as it were, 90° with respect to the formations in the other end turn. This permits, when the coils are placed closer together than illustrated in Fig. 1, such as portion 217 being immediately adjacent the portion 215-214 of the adjacent coils in the same row, the same helical tie arrangement to be utilized with the bottom turns of the several coils as is utilized with respect to the top turns thereof, as illustrated in Fig. 1, with the distinction that the helices 219 in the bottom plane (see Fig. 3) in this instance have axes transverse to the axes of the helices 219 in the top plane of Fig. 3.

The purpose of this 90° positioning when desired, is it may be highly desirable to stabilize the bottom of a spring unit against movement in one direction whereas the top of the unit requires stabilization in a transverse direction. This, the aforesaid structural arrangement accomplishes.

It also is to be understood, as previously set forth, that the spring shown in Fig. 1 may have its lower end turn formations when the spring is of double conical type, similarly offset 90° with respect to the top turn formations. Also, it is to be understood that double conical coils of the character illustrated in Figs. 1 and 2 may have their top turns connected together and bottom turns connected together by helices which are substantially parallel, referring to the top and bottom helices and to accomplish the same, it is to be understood that the double conical coil in each instance is forcibly twisted so that one of its end turns is rotated in the winding direction 90°. This modifies the tension of each of the coils.

This also, it is quite obvious, translates the relationship between the free ends and the adjacent offset portions.

By bringing out the curved portion 115 and shortening portion 114 in Fig. 2 and bringing out the tangential portion 14 and shortening curved portion 15 in Fig. 1, there is provided an extra area of support in the end plane of the coils. The formation in both forms of the invention disclosed is such that there is, provided with respect to the portions 12 and 16, and 112 and 116, an arrangement that is of considerable force resisting character—in other words, this portion of each spring has increased resistance to spring deformation under load. Various other advantages also accrue from the utilization of either of these two embodiments of the invention.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claim.

The invention claimed is:

A spring unit wherein the top and bottom lie in substantially parallel planes and are similar to each other, said unit including a plurality of coil springs, each having at opposite ends end

turns lying in said planes, the several springs being arranged in rows substantially transverse to each other, springs in adjacent parallel rows being substantially tangential at their end turns, helices between adjacent rows connecting the tangential end turns of adjacent springs together, all the helices in the bottom plane being transverse to all those in the top plane, each end turn of each coil spring having a predetermined formation, the opposite end turn formations of said each coil being similar but angularly displaced 90° about the longitudinal axis of the coil, each coil end turn formation including an elongated free end, the start of the end turn in

5 that coil having a similarly elongated portion and in longitudinal alignment with the said elongated free end and the said end turn, intermediate said aligned portions, having an elongated portion approximately midway between said first mentioned aligned portions and outwardly offset from the immediately adjacent portions of said end turn, the helices having operative connection with the several aligned and offset portions of the coils, and top and bottom border wire means operatively connected with all marginal coils at the top and bottom end turns thereof for unit formation.

WILLIAM E. WUNDERLICH.
